Inventor:

W. D. SEAL,

By *W. J. Fitzgerald & Co.*

Attorney.

UNITED STATES PATENT OFFICE.

WILLIAM D. SEAL, OF DES ARC, MISSOURI.

WRENCH.

Application filed August 21, 1923. Serial No. 658,575.

To all whom it may concern:

Be it known that I, WILLIAM D. SEAL, a citizen of the United States, residing at Des Arc, in the county of Iron and State of Missouri, have invented certain new and useful Improvements in Wrenches; and I do hereby declare the following to be a full, clear, and exact description of the invention, such as will enable others skilled in the art

10 to which it appertains to make and use the same.

The present invention relates to wrenches and similar tools, and one object of the invention is the provision of novel swivel and 15 ratchet connection between the head and actuating member of the tool whereby the head can be turned by the oscillation of the actuating member, and whereby the head can be removed so that several heads can 20 be used interchangeably with the same actuating member.

Another object is the provision of a novel chuck head which is adjustable for different sizes of nuts or other objects.

25 It is also an object of the invention to provide such a device comprising a novel assemblage of the component elements, whereby the device is practical and efficient in use.

30 With the foregoing and other objects in view, which will be apparent as the description proceeds, the invention resides in the construction and arrangement of parts as hereinafter described and claimed, it being 35 understood that changes can be made within the scope of what is claimed, without departing from the spirit of the invention.

The invention is illustrated in the accompanying drawings, wherein—

40 Figure 1 is a side elevation of the implement including the chuck head;

Fig. 2 is an enlarged median section of the chuck head and connection between said head and actuating member, portions being 45 shown in elevation;

Fig. 3 is a fragmentary section of the chuck head showing the jaws in another position;

Fig. 4 is a section on the line 4—4 of Fig.

50 2;

Fig. 5 is an end view of the chuck head;

Fig. 6 is an elevation showing the use of a brush head with the actuating member; and

55 Fig. 7 is a median section of said brush head with the bristles retracted.

The implement uses a crank or brace 10 as an actuating member, having the knob or handle 11 swiveled on one end thereof, and having the actuating handle 12 on the crank 60 proper for conveniently rotating the crank. The crank is provided at its other end with the ring 13 having the opening 14, said ring being concentric with the axis of rotation of the crank.

65 The ring 13 is adapted to receive the head, which, as shown in Figs. 1-5, includes the tubular shell or case 15. One end portion of the shell or member 15 is adapted to fit rotatably in the opening 14, for swivel connection with the crank or actuating member 10, and in order to retain the shell 15 in connection with the crank 10, said shell or member 15 is provided with an annular groove 16 for receiving a retaining member 17 carried by the crank 10. Said retaining member 17 is of arcuate form to bear against the shell 15 within the groove 16, and the ring 13 has a recess 18 in which said member 17 is movable into and out of the opening 14. The member 17 has a stem 19 projecting slidably into the crank, and a coiled spring 20 surrounds said stem and is confined between the member 17 and the crank, whereby to yieldingly project said member 80 into the opening 14 and groove 16, for holding the crank and head or member 15 assembled. A button or finger piece 21 is secured to the stem 19 and is slidable in a slot 22 in the crank for conveniently reTRACTING the member 17 from the opening 14 and groove 16, when it is desired to remove 85 the shell or member 15.

90 A ratchet connection between the shell or member 15 and crank is also provided, 95 whereby the head can be rotated by the oscillation of the crank, as well as by the rotation of the crank. Thus, a pawl or dog 23 is slidable in a hole 24 in the ring 13, and has a stem 25 slidable through a plug 100 26 screwed or otherwise secured in the outer end of said hole, and the stem has a finger piece or handle 27 at its outer end for convenience in retracting the pawl. A coiled spring 28 is confined between the pawl 23 and plug 26 for yieldingly projecting the pawl into the opening 14 and groove 16 to snap into engagement with the ratchet notches 29 provided in the shell or member 15 at the bottom of the groove 16. The shell 15 can thus be made to rotate with the crank, and when it is not possible to ro-

tate the crank, it can be oscillated, whereby the ratchet connection between the crank and shell 15 will turn the shell with an intermittent motion, as will be apparent. 5 The finger piece 27 enables the pawl 23 to be retracted, in order that the pawl can be turned around or reversed, for rotating the shell 15 in either direction, and the pawl 23 is also retracted, when the retaining member 17 is retracted, for the removal or insertion of a head, it being understood that different heads can be used interchangeably with the crank, providing the heads are of a size to fit in the opening 14 and have the 10 groove 16 and notches 29.

In Figs. 1-5 there is illustrated a chuck head to enable the tool to be used as a wrench for turning nuts, bolts and other objects of different sizes. Such chuck head 20 includes a block or member 30 slidable within the shell 15, and arms 31 pivoted, as at 32, to the block 30 and provided with jaws 33 at the open or outer end of the shell 15. As shown, there are three arms 25 31, although there may be different numbers of said arms. The jaws 33 have the angular faces or recesses 34 confronting one another for engaging the angles of nuts, bolt heads, and the like, although the faces 39 of the jaws may be of different formations. The backs 35 of the jaws are beveled or disposed obliquely with reference to the jaws and arms, to bear against the enlarged tapered end portion 36 of the shell, so that the 35 jaws are forced toward one another when they are projected from the shell, and are permitted to separate when retracted into the shell. This enables the jaws to be adjusted for nuts, bolt heads, and other objects of 40 different sizes, within the limits of adjustment. In order to assist in the opening and closing of the jaws when they are slid inwardly and outwardly, headed screws or studs 37 are engaged with the arms 31 or 45 jaws 33 thereof and work in slots 38 in the portion 36 of the shell, thereby keeping the backs 35 of the jaws against said portion 36.

The block 30 is adjusted longitudinally, to adjust the jaws, by means of a screw 39 50 swiveled through the inner end portion of the shell 15, and, as shown, the screw has an annular groove 40 receiving a set-screw 41 carried by the shell 15. The screw 39 is screwed into the block 30, and said screw 55 has a thumb-piece or knob 42 at its inner end for convenience in rotating the screw, whereby to move the block 30 longitudinally in the shell. Thus, by turning the knob or finger-piece 42, the block 30 can be slid 60 in one direction or the other for moving the jaws 33 inwardly or outwardly for opening or closing the jaws. Such jaws can thus be conveniently adjusted for nuts, bolt heads, and other objects of different sizes. 65 Figs. 6 and 7 show a brush head to be

used with the crank or actuating member for cleaning out carbon from internal combustion engines, or for cleaning out other cavities or chambers. The brush head includes a tubular shell 15', one end portion 70 of which is of a size to fit in the opening 14 of the crank, and provided with the groove 16 and notches 29 for the engagement of the retaining member 17 and pawl 23, respectively. A block or member 30' is 75 slidable in the shell 15', and is actuated by the screw 39' swiveled through the inner portion of the shell and provided with the knob or finger-piece 42' at its inner end. Wire or other resilient bristles 33' are secured to the block or member 30' in any suitable manner, to be retracted into the shell 15', as seen in Fig. 7. The bristles are so bent, that when they are projected from the shell, they will spread apart or open out so as to enter 80 a chamber or cavity into which the bristles are projected.

Fig. 6 illustrates the brush head as used for cleaning out carbon from the combustion chamber of an internal combustion engine. 85 The end of the shell 15' is inserted in an opening 43 in the cylinder head, from which the plug has been removed, and the bristles 33' are retracted in the shell so that the shell can be conveniently inserted. Then, the finger-piece or knob 42' is turned so as to project the bristles from the shell, and said bristles will open out or spread apart so as to come into contact with the walls 90 of the combustion chamber throughout the extent of said walls, and by rotating the crank 10, the bristles are rotated in the chamber for brushing the carbon loose, so that it can be blown out from the combustion chamber. Such brush head is especially 95 useful for cleaning carbon from engines in which the cylinder heads are not removable, and the brush head can be used for cleaning out or brushing other cavities or chambers to which access is only had through a restricted hole or opening.

When the bristles are retracted into the shell, they can be conveniently inserted through or withdrawn from the hole or opening leading to the cavity or chamber. 110

The chuck and brush heads can thus be used interchangeably with the crank or actuating member, and other heads can also be used with said crank. Chuck heads of different kinds can be used interchangeably 115 for nuts, bolts, and other objects of different sizes and shapes, and the jaws can also be formed to engage screw-threads of stud bolts and the like.

Having thus described the invention, what 120 is claimed as new is:—

1. A tool comprising an actuating member having a circular opening therein, a head having a cylindrical portion fitted rotatably and removably in said opening coaxial with 125

said opening, said head having an annular groove and ratchet notches between the sides of the groove, a retaining member movably mounted in said actuating member and 5 adapted to project into said opening and fit snugly in said groove, a pawl independent of said retaining member mounted movably in the actuating member to project into said opening and engage said ratchet notches, 10 and spring means for moving said retaining member and pawl into said opening to engage in said groove and notches respectively, said retaining member and pawl being adapted to be retracted from said opening to 15 permit the head to be withdrawn from the opening.

2. A tool head comprising a shell having a tapered portion provided with longitudinal slots, a member movable longitudinally in said shell, jaws pivoted to said member having portions bearing against said tapered portion for swinging the jaws toward one another when said member is moved in one direction, the jaws having members working in said slots for swinging the jaws away 25 from one another when the first-named member is moved in the opposite direction, and means for moving said first-named member longitudinally within said shell.

In testimony whereof I have signed my 30 name to this specification.

WILLIAM D. SEAL.
